COMBINED CONTROL PANEL AND SWITCH

Robert D. Kahn, Rockville Centre, N.Y., assignor to
Fedtro, Inc., Rockville Centre, N.Y.

Filed Feb. 3, 1971, Ser. No. 112,517

Term of patent 14 years

Int. Cl. D13—03

U.S. Cl. D26—13

FIG. 1

FIG. 2

FIG. 1 is a front perspective view showing a combined control panel and switch according to the present invention;

FIG. 2 is a back elevational view thereof;

FIG. 3 is a top plan view thereof;

FIG. 4 is a bottom plan view thereof; and

FIG. 5 is a side elevational view thereof, taken from the right side.

The cord is shown broken away in FIGS. 1-5 to denote indeterminate length thereof.

I claim:

The ornamental design for a combined control panel and switch, as shown and described.
